DEMOUNTABLE SUPPORT FOR BEDSPRINGS

Joseph Shapiro, Shrub Oak, N. Y.

Application August 18, 1948, Serial No. 44,963

12 Claims. (Cl. 5—310)

1

This invention relates to beds and sofas and in particular is directed to the provision of supporting means for a bedspring whereby the same may be readily adapted for use as a bed or a sofa.

The clumsiness of the conventional bed comprising the bedstead and spring (upon which the mattress is placed) restricts the use of such structure to a bedroom. Where it is desired particularly to provide a bed that does not occupy as much cubic footage as the ordinary bed or to provide a living room with a structure that may be utilized during the daytime for sitting and at nighttime for sleeping, the structures used have been either cots or couches having inadequate springs or complicated structures of the folding character which are opened at night. Some of the latter devices are exceedingly intricate in construction and costly, especially where they are provided with strong, sound springs.

I have conceived of a means whereby a strong, sturdy bedspring may be readily, easily and cheaply provided with a set of supports of relatively simple construction, said supports being easily affixed or removed, so that a structure can be made available with minimum expense which affords either seating or sleeping accommodations.

Accordingly it is among the objects of this invention to provide a novel support of relatively simple construction which may be readily affixed to the frame of a bedspring, whereby the bedspring is converted into a structure that may be used both as a seat and as a bed.

Further objects will become apparent from the following more detailed description of my invention taken in connection with the accompanying drawing wherein

Fig. 1 is an illustrative partial representation, in perspective, showing a bedspring provided with readily mounted and demountable supports.

Fig. 2 is a front elevation of one of the legs forming a part of the supports illustrated in Fig. 1.

Fig. 3 is a top plan view of the leg illustrated in Fig. 2.

Fig. 4 is an illustration, partly broken away, showing the upper portion of the leg illustrated in Fig. 2 and clamping member forming the support in mounted assemblage with the frame (shown in cross section) of the bedspring illustrated in Fig. 1.

Fig. 5 is a side elevation of the structural arrangement illustrated in Fig. 4.

Fig. 6 is another embodiment of the support

2

illustrated in Fig. 4, the clamping member and leg being of modified form.

Fig. 7 is a side elevation of the structure illustrated in Fig. 5.

Fig. 8 is a further embodiment of the support illustrated in Fig. 4, the clamping member and leg being of modified form.

Fig. 9 is a top plan view of the structure illustrated in Fig. 8.

Fig. 10 is an illustrative partial representation, in perspective, showing another form of the bedspring, wherein the frame comprises a round or tubular rail, as mounted upon a further modified form of support.

Fig. 11 is an enlarged partial sectional view of the modified form of support of Fig. 10, the bedspring-supporting leg being shown partially broken away.

Fig. 12 is a view of the bridging plate taken on the line 12—12 of Fig. 11.

Fig. 13 is a side elevational view of the upper portion of the assemblage illustrated in Fig. 11.

In its fundamental aspects, the primary object of my invention is achieved by a bedspring support which comprises a yoke that is adapted for mounting over a bedspring rail, a leg, supporting said rail and adapted to be engaged by the yoke, and means for clamping the yoke, the leg and the rail in rigid assembled relationship.

Referring now to the drawings, and particularly with reference to Fig. 1 and its associated figures, the numeral 20 designates a bedspring, the frame of which comprises a rail 22. To this rail there is rigidly affixed or clamped a demountable support 24 which comprises a yoke 26 of metal or other suitable material and a rail supporting leg 28 of wood or other appropriate material, said leg and the short sides of the yoke being adapted for engagement with each other. The whole assemblage of the yoke 26, the rail 22 and the leg 28 are tightly held together by fastening means 30 or other appropriate clamping device.

In this instance the rail 22 is formed of an angle iron 32 having a vertical member 34 and a horizontal member 36. The leg 28 is provided with a vertical slot 38 into which the vertical member 34 of the rail is fitted. The horizontal member 36 of the rail rests upon the upper surface 40 of the leg 28. The yoke 26 comprises the base 42 and the legs 44 and 46, the latter terminating in in-turned wings 48 and 50 respectively which are engaged by the horizontal slots 52 and 54 respectively of the leg 28. The base 42 is provided with a threaded aperture 56 which is adapted to receive the thumb-screw 58 of the

clamping means 30 or other appropriate device, the thumb-screw being tightened against the horizontal member 36 of the angle iron. When four of such legs are affixed to the rail, two on each side, there is provided a sturdy structure which is adapted to function, by the use of a mattress or similar device, both as a seat and as a bed.

In the modified form of the bedspring support illustrated in Fig. 6 the yoke, instead of being a unitary piece as illustrated in Fig. 4, comprises a base plate 60 and two side members 62 and 64. The side members are provided with slots 66 and 68 respectively through which the ends 70 and 72 of the base plate protrude, thus bridging the side members. The side members 62 and 64 are bored as at 74 to permit of the insertion of means for fastening the side members to the leg 76 as by wood-screws 80 or the like. The leg 76 is provided with a vertical slot 82 for the reception of the vertical member 34 of the angle rail. The base plate 60 is provided, in a manner similar to the base 42, with a threaded aperture 84 into which is set the thumb-screw 86, thus providing for the clamping of the assemblage of the yoke, the rail-supporting leg, and the rail in rigid relationship upon the tightening of the thumb-screw.

This form of structure may be assembled by affixing the side members 62 and 64 to the upper portion of the leg 76, leaving sufficient room to allow the slots 66 and 68 thereof to extend above the upper surface of the leg and allow for setting the vertical member of the angle rail within the slot 82 and allow for the insertion of the bridging plate 60, the ends thereof being engaged by the slots. Upon insertion and tightening of the thumb-screw the entire assemblage will be rigidly clamped.

In the embodiment illustrated in Figs. 8 and 9 the yoke of the spring support comprises a structure which is in part a combination of (a) the structure of the yoke illustrated in Fig. 4 and (b) the structure illustrated in Fig. 6. In this modification the base of the yoke comprises a horizontal member 90 and an integral side consisting of the vertical member 92 which terminates in an in-turned wing 94. The other side of the yoke is formed of a plate 96 having a slot 98 for the reception and engagement of the end 100 of the horizontal member 90. The plate is bored as at 102 for the reception of screws 104 or other similar devices whereby said plate may be affixed to the leg 110. The leg 110 is provided with a vertical slot 112, similar to the corresponding slots of the legs illustrated in Figs. 4 and 6, for the reception of the vertical member of the rail angle. One side of the leg is provided with a horizontal slot 114 within which is engaged the wing 94. The base 90 is provided with a threaded aperture 116 into which may be inserted a thumb-screw 118 or other similar device for the rigid clamping of the yoke, the leg and the rail.

In assembling this form of structure the plate 96 is affixed to the upper end of the leg 110 by the screws 104 so as to allow the slot 98 thereof to be positioned for the reception and engagement of the base of the yoke 90 after the angle rail has been set within the slot 112, and the wing 94 securely positioned within the horizontal slot 114. Thereupon the thumb-screw 118 is tightened against the horizontal member of the angle rail and the bedspring support thus securely clamped to the bedspring rail.

As shown in Fig. 10 and its associated figures, the numeral 150 designates a form of bedspring in which the frame comprises a tubular rail 152. The bedspring support 154 comprises a yoke 156, mounted over the rail 152, and a tubular leg 158 on which the rail rests, held, in threaded engagement, within a plate which bridges the sides or legs of the yoke.

The yoke 156 formed of metal or other appropriate material comprises a base 160 and sides or legs 162 and 164, the latter being provided with slots 166 and 168 respectively through which protrudes a plate 170 bridging said sides and being supported thereby. The ends 172 and 174 of the plate 170 may be of such length as will securely effectuate the bridging. The plate 170 is provided with a threaded bore 176 adapted to receive the upper end of the tubular leg 158, threaded as at 178. The base 160 of the yoke is provided with apertures 180 into which may be inserted means such as a set-screw or thumb-screw 182 for rigidly tightening the yoke against the upper side of the rail 152. In affixing this form of support to the bedspring the yoke 156 is laid upon the rail 154. Then the bridging plate 170 is inserted within the slots 166 and 168 so as to be held in engagement thereby and the tubular leg 158 is screwed into the bridging plate 174 and it may be tightened until it securely engages the rail 154. In order to provide a broader supporting surface for the rail 152, a bearing member or pillow block 186 may be used. The base 188 of such bearing member may be set within the upper hollow end of the tubular leg 158, and the rail then rested upon the bearing surface 190 of said pillow block. Then for the better clamping of the rail 154, the tubular leg 158, and the yoke, the screws 182 are tightened until the desired rigidity of the assemblage is attained. The lower end of the tubular leg 158 may be fitted with a rubber or other appropriate device 184.

It will be understood that the form of support thus described may also be used to support a bedspring in which the rail is an angle, as shown in Fig. 1 and the associated figures, instead of the tubular rail shown in Fig. 10 and the associated figures. In such case the horizontal member of the angle rail lies directly on the top of the tubular leg 158 (the bearing member 186 being removed) while the vertical member of such angle rail may lie against the tubular leg, and the base 160 of the yoke lies on the horizontal member of the angle rail. Such an assemblage is held in rigid relationship by tightening the screws, set within the base of the yoke, against the upper surface of the horizontal member of the angle rail.

It will be observed that my invention makes it possible for a person quickly and easily to affix my novel supports to the frame of a bedspring so that the same may be used for the purposes indicated. It will also be obvious that if it is desired to disassemble the erected structure, the same may be done speedily without the use of any special tools. Furthermore, if it is desired to provide for extreme sturdiness or rigidity, there may be used, in addition to the four corner legs normally used, any additional number of supports appropriately positioned underneath the bedspring.

It will be understood that the foregoing embodiments hereinabove described are merely illustrative of the principle of my invention and accordingly the appended claims are to be under-

stood as defining my invention within the full spirit and scope thereof.

I claim:

1. A demountable support for attachment to the frame of a bedspring to maintain the same in elevated position comprising: a yoke adapted for mounting over the rail of a frame of a bedspring; said yoke having a flat base and sides, the sides having in-turned wings at the ends thereof; a leg adapted to support the aforesaid rail, the said rail being in the form of an angle, said leg having a vertical slot to receive the vertical member of the rail and horizontal slots adapted to receive the aforesaid wings, and the upper surface of the leg being adapted to support the horizontal member of the aforesaid angle rail; and adjustable fastening means set within the base of the yoke whereby the yoke, the leg, and the rail may be clamped in rigid assembled relationship.

2. A demountable support for attachment to the frame of a bedspring to maintain the same in elevated position comprising: a yoke adapted for mounting over the rail of the frame of a bedspring, said yoke having a flat base, sides, and means for fastening said sides to a leg; a leg adapted to support the aforesaid rail, said rail being in the form of an angle, said leg having a vertical slot to receive the vertical member of the angle, and the upper surface of said leg forming a support for the horizontal member of the aforesaid angle rail; and adjustable fastening means set within the base of the yoke whereby the yoke, the leg, and the rail may be clamped in rigid assembled relationship.

3. A demountable support for attachment to the frame of a bedspring to maintain the same in elevated position comprising: a yoke adapted for mounting over the rail of the frame of a bedspring, said yoke having an integral base and sides, said sides terminating in in-turned wings; a leg adapted to support the aforesaid rail, said rail being in the form of an angle, said leg having a vertical slot adapted to receive the vertical member of the aforesaid angle, the upper surface of the leg providing a support for the horizontal member of the aforesaid angle rail; horizontal slots in the leg adapted to receive the aforesaid wings; and adjustable fastening means set within the base of the yoke whereby the yoke, the leg, and the rail may be clamped in rigid assembled relationship.

4. A demountable support for attachment to the frame of a bedspring to maintain the same in elevated position comprising: a yoke adapted for mounting over the rail of the frame of a bedspring, said yoke having a base and one side integral with said base, said side having an in-turned wing; the second side of said yoke being a plate having a slot adapted to engage the aforesaid base; a leg adapted to support the aforesaid rail, said rail being in the form of an angle, said leg having a vertical slot adapted to receive the vertical member of the angle, the upper surface of the leg being adapted to support the horizontal member of the aforesaid angle rail; a horizontal slot in the leg adapted to receive the aforesaid wing of the side of the yoke integral with the base; means for fastening the second side of the yoke to the leg; and adjustable fastening means set within the base of the yoke whereby the yoke, the leg, and the rail may be clamped in rigid assembled relationship.

5. A demountable support for attachment to the frame of a bedspring to maintain the same

in elevated position comprising: a yoke adapted for mounting over the rail of the frame of a bedspring, said yoke comprising a base plate and sides in the form of a pair of plates having slots for engaging the ends of the base plate; a leg adapted to support the aforesaid rail, the said rail being in the form of an angle, said leg having a vertical slot to receive the vertical member of the angle, the upper surface of the leg being adapted to support the horizontal member of the aforesaid angle rail; means for fastening the side plates of the yoke to the leg; and adjustable fastening means set within the base of the yoke whereby the yoke, the leg, and the rail may be clamped in rigid assembled relationship.

6. A demountable support for attachment to the frame of a bedspring to maintain the same in elevated position comprising: a yoke adapted to be mounted over the rail of the frame of a bedspring, the sides of said yoke being provided with slots adapted to engage a plate bridging said sides, said bridging plate having a threaded orifice adapted to receive a threaded leg for supporting the aforesaid rail; a leg engaged within said bridging plate, the said leg being adapted to engage a bearing member; and a threaded hole in the base of the yoke adapted to receive a threaded member whereby the yoke, the leg, and the rail may be clamped in rigid assembled relationship.

7. A demountable support for attachment to the frame of a bedspring to maintain the same in elevated position comprising, a yoke, a leg, an adjustable fastener, and means carried by the yoke for cooperation therewith for clamping the said yoke, the rail, and the leg in rigid assembled relationship with upper surface of the leg in engagement with said rail.

8. A demountable support for attachment to the frame of a bedspring to maintain the same in elevated position comprising: a yoke adapted to be mounted over the rail of the frame of a bedspring, the sides of said yoke being provided with slots, a bridging plate carried by the walls of said slots, a leg carried by said bridging plate, and adjustable fastening means set within the base of said yoke whereby the said yoke, the rail, and the leg may be clamped in rigid assembled relationship.

9. A demountable support for attachment to the frame of a bedspring to maintain the same in elevated position comprising: a yoke adapted to be mounted over the rail of the frame of a bedspring, the sides of said yoke being provided with slots, a bridging plate carried by the walls of said slots, a leg carried by said bridging plate, the said leg having at its upper end a rail bearing member, and adjustable fastening means set within the base of said yoke whereby the said yoke, the rail, and the leg may be clamped in rigid assembled relationship.

10. A demountable support for attachment to the frame of a bedspring to maintain the same in elevated position comprising: a yoke adapted to be mounted over the rail of the frame of a bedspring, the sides of said yoke being provided with slots, a bridging plate carried by the walls of said slots, the said bridging plate having a threaded orifice, a leg carried by said bridging plate, the said leg being threaded to engage the threads of the orifice of the bridging plate, and adjustable fastening means set within the base of said yoke whereby the said yoke, the rail, and the leg may be clamped in rigid assembled relationship.

11. A demountable support for attachment to the frame of a bedspring to maintain the same in elevated position comprising: a yoke adapted to be mounted over the rail of the frame of a bedspring, the sides of said yoke being provided with slots, a bridging plate carried by the walls of said slots, the said bridging plate having a threaded orifice, a leg carried by said bridging plate, the said leg being threaded to engage the threads of the orifice of the bridging plate, the 10 said leg also having at its upper end a rail bearing member, and adjustable fastening means set within the base of said yoke whereby the said yoke, the rail, and the leg may be clamped in rigid assembled relationship.

12. A demountable support for attachment to the frame of a bedspring to maintain the same in elevated position comprising: a yoke adapted to be mounted over the rail of the frame of a bedspring, the sides of said yoke being provided 15

5 with slots, a bridging plate carried by the walls of said slots, the said bridging plate having a threaded orifice, a leg carried by said bridging plate, the said leg being threaded to engage the threads of the orifice of the bridging plate, and adjustable threaded fastening means set within the base of said yoke whereby the said yoke, the rail, and the leg may be clamped in rigid assembled relationship.
